(57) **CLAIM**

The ornamental design for a gauge dial housing, as shown and described.

DESCRIPTION

FIG. 1 is a front view of the gauge dial housing;
FIG. 2 is a top view of the gauge dial housing;
FIG. 3 is back view of the gauge dial housing;
FIG. 4 is a bottom view of the gauge dial housing;
FIG. 5 is a perspective view of the gauge dial housing;
FIG. 6 is a right side view of the gauge dial housing; and,
FIG. 7 is a left side view of the gauge dial housing.
The portions in broken lines showing other parts are for
illustrative purposes of depicting the environment only and
form no part of the claimed design.
